RAILWAY TRAFFIC CONTROLLING APPARATUS

Frank H. Nicholson and Harold W. Bryan, Penn Township, Allegheny County, Pa., assignor to The Union Switch & Signal Company, Swissvale, Pa., a corporation of Pennsylvania

Application September 4, 1941, Serial No. 409,492

6 Claims. (Cl. 246—63)

Our invention relates to railway traffic controlling apparatus, and particularly to automatic train controlling apparatus of the intermittent inductive type.

Intermittent inductive train control and cab signal systems ordinarily provide but one proceed indication. The trend toward higher train speeds and longer trains makes the provision of an additional proceed indication desirable.

Accordingly, a feature of our invention is the provision of railway traffic controlling apparatus organized into a novel and improved intermittent inductive three-position train control and cab signal system.

Another feature of our invention is the provision of railway traffic controlling apparatus of the type here involved incorporating novel and improved means to eliminate the possibility of a false proceed indication.

Again, a feature of our invention is the provision of relatively simple and inexpensive apparatus for an intermittent inductive three-position train control and cab signal system.

Other features, advantages and objects of our invention will appear as the specification progresses.

To attain the foregoing features, objects and advantages of our invention we provide two trackway or roadside inductors in tandem on one side of the track at each control point or signal location along the railway. The two inductors of a control point are governed to different conditions in response to different traffic conditions in advance and in each of such conditions two successive control influences are transmitted to a train carried receiver as the train passes such control point. Each such combination of two successive control influences is made distinctive so that each different traffic condition is reflected by a distinct combination of two successive control influences. In the particular form of the invention here contemplated, clear traffic condition is reflected by a combination of control influences in which the first of the two control influences creates a predetermined higher than normal electromotive force in a train carried receiver, and the second influence causes no change in a predetermined normal electromotive force in such receiver. Under approach traffic conditions in advance, the first transmitted influence of the combination creates the previously mentioned predetermined higher than normal electromotive force in the train carried receiver, but the second influence creates a predetermined less than normal electromotive force. Under stop or slow speed traffic conditions in advance, each of the two control influences of the combination creates the previously mentioned less than normal electromotive force in the train carrier receiver.

On the train we provide signaling apparatus that includes a receiver having a winding and means to create an electromotive force in the winding, a group of control relays governed to different positions by the electromotive forces created in the receiving winding, and a cab signal and train controlling mechanism selectively governed to different positions by the control relays. The receiver is disposed for inductive relationship to the roadside inductors and the value of the electromotive force created in the receiver winding is governed by the character of the control influence transmitted by a roadside inductor so that at each control point the two control influences transmitted create two predetermined values of electromotive force in the receiver winding.

In the instant case, three predetermined values of electromotive force are provided, namely, a predetermined normal value, a predetermined higher than normal value and a predetermined lower than normal value. A first one of the control relays is adjusted for a pick-up electromotive force which corresponds to the higher than normal electromotive force and with a release electromotive force which corresponds to the lower than normal electromotive force. A second control relay is adjusted for a pick-up electromotive force which corresponds to the normal electromotive force and with a release electromotive force which corresponds to the lower than normal electromotive force. A third control relay is a stick relay controlled by the first and second relays.

The first and second relays are connected to the receiver winding over a receiving circuit having alternative circuit paths which are interlocked in a novel manner to cause the three relays to respond in a distinct arrangement for each of the different combinations of two control influences transmitted by the two roadside inductors of a control point. The interlocking of receiving circuit paths for the control relays is also such as to eliminate a false arrangement of the relays being effected due to a wrong control influence. We use these three control relays to selectively govern the different positions of a cab signal and of a brake controlling magnet, so that preselected positions of the cab signal and brake controlling magnet are established for each particular combination of control influences, that is, for each different traffic condition.

We shall describe one form of apparatus embodying our invention, and shall then point out the novel features thereof in claims.

In the accompanying drawing, Figs. 1 and 2 when taken together are a diagrammatic view showing one form of apparatus embodying our invention, Fig. 1 illustrating the roadside portion

of the apparatus and Fig. 2 illustrating the train carried portion of the apparatus.

Referring to Fig. 1, the reference characters $1a$ and $1b$ designate the rails of a stretch of railway over which traffic normally moves in the direction indicated by an arrow and which stretch is formed by the usual insulated rail joints with successive track sections of a signal system. The two full sections $D-E$ and $E-F$, together with the adjacent ends of the two adjoining sections only are shown since these are sufficient to illustrate the principles of our invention. Each section is provided with a track circuit which comprises a source of current, such as a battery 10 , connected across the rails at one end of the section and a track relay designated by the reference character TR plus a prefix corresponding to the location connected across the rails at the other end of the section. Each section is also provided with a line circuit which includes a line relay designated by the reference character DR plus a prefix corresponding to its location, and which circuit is controlled by traffic conditions in the section next in advance. For example, the line circuit for section $E-F$ includes a line relay EDR and is controlled over front contact 11 of track relay FTR for the section next in advance of section $E-F$. The line circuit for each of the other sections is of a similar arrangement.

Automatic wayside signals, one at the entrance end of each track section, are preferably provided, such signals being identified by the reference character S plus a prefix corresponding to the location. The type of wayside signal is immaterial and any standard type of three-position signal may be used. Each such signal is controlled by circuits governed by the track and line circuits of the associated section, but such signal control and operating circuits are not shown since they would be in accordance with standard practice and form no part of our present invention. It is sufficient for the present application to point out that a wayside signal is set to display a stop indication when the section immediately in advance is occupied, is set to display an approach signal indication when the immediate section in advance is unoccupied and the second section in advance is occupied, and is set to display a clear signal indication when at least the two sections next in advance are unoccupied.

Trackway or roadside elements designated by the reference characters $A1$ and $A2$, respectively, plus a prefix corresponding to the location are provided for each section. These two roadside elements for each section are installed on one side of the track in a tandem arrangement and are preferably installed just to the rear of the entrance end of the section. The two elements are also disposed a short distance apart. These trackway elements may take any one of several different forms and are preferably all alike. One form of trackway element that may be used is that of the roadside inductor disclosed in Letters Patent of the United States No. 1,843,477, granted February 2, 1932, to Paul N. Bossart, for Railway traffic controlling apparatus. As shown in Fig. 1, the roadside elements are of the inductor type of the above Bossart patent and it is sufficient for this application to point out that inductor $DA1$, for example, comprises a magnetizable core 12 and a winding 13 mounted thereon, core 12 having to poles $12a$ and $12b$. As stated hereinbefore, each of the other inductors is of a similar construction.

The two inductors of a section are governed by the track and line circuits of that section. Looking at the inductors $DA1$ and $DA2$ for track section $D-E$, inductor $DA1$ which is the first inductor passed by a train about to enter the associated section $D-E$ when moving in the normal direction of traffic, is controlled over a circuit that extends from the right-hand terminal of its winding 13 , wire 14 , front contact 15 of track relay DTR , wire 16 , a condenser 17 and to the left-hand terminal of winding 13 . The second inductor $DA2$ is controlled over a circuit that extends from one terminal of its winding 13 , wire 18 , front contacts 19 and 20 of relays DTR and DDR , respectively, and wire 21 to the other terminal of its winding 13 . In other words, the winding 13 of the first inductor $DA1$ is short circuited through condenser 17 when the associated track relay DTR is picked up, and the winding 13 of the second inductor $DA2$ is short circuited when both the associated track and line relays are picked up. Hence under clear traffic conditions in advance of the control point D and both track relay DTR and line relay DDR are picked up, the windings of both inductors $DA1$ and $DA2$ are short circuited, condenser 17 being interposed in the circuit for inductor $DA1$. Under approach traffic conditions in advance of control point D and track relay DTR is picked up and line relay DDR is released, the winding of the first inductor $DA1$ is short circuited as before and the winding of the second inductor $DA2$ is open circuited. Under stop or slow speed traffic conditions in advance of control point D and track relay DTR is released, the windings of both inductors $DA1$ and $DA2$ are open circuited. The circuits for the other pairs of inductors are controlled in a manner similar to that just described for inductors $DA1$ and $DA2$ and will be readily understood by an inspection of Fig. 1.

Since the reluctance of each roadside inductor is varied according as its winding is open circuited or short circuited, and is further varied according as its circuit connection includes a condenser or not, it follows that each pair of roadside inductors of Fig. 1 is adaptable of being conditioned to create different combinations of two control influences taken from a group of three influences. The manner whereby the different combinations of two control influences effected by each pair of roadside inductors according to different traffic conditions are used to control the cab signal apparatus of Fig. 2 will be pointed out when the operation of the apparatus is described.

Referring to Fig. 2, the reference character AT designates a train carried receiver which cooperates with the roadside inductors of Fig. 1 for receiving on the train control influences according to the different conditions of the roadside inductors. The receiver AT may take any one of several different forms and the form shown in Fig. 2 is that disclosed in the aforementioned Bossart Patent No. 1,843,477 and to which patent reference is made for a full description of such a train carried receiver. It is sufficient for this application to point out that receiver AT comprises a primary winding 24 and a secondary winding 25 mounted on a magnetizable core structure having two poles 22 and 23 . This core structure is analogous to the electric circuits of the well-known Wheatstone bridge, the air gaps 28 and 29 forming two arms of the bridge, and the air gap between poles 22 and 23 and the air gap 31 forming the other two arms of the bridge.

75 Receiver AT is mounted on the train in a posi-

tion that its poles 22 and 23 pass over the poles of the roadside inductors with proper clearance. Thus when poles 22 and 23 are above the two poles of a roadside inductor the air gap between the poles 22 and 23 is varied by the core of the roadside inductor and the Wheatstone bridge arrangement of the core of the receiver AT is influenced. The extent of such influence on the receiver AT depends upon the closed or open circuited condition of the winding of the roadside inductor and also upon the presence or absence of a condenser in the inductor circuit. Thus as here shown there are three possible influences impressed upon the receiver AT; one when the roadside inductor winding is open circuited, a second one when the inductor winding is short circuited and a third influence when the inductor winding is short circuited through a condenser.

Primary winding 24 is constantly supplied with alternating current from a generator G1, the circuit for winding 24 preferably including a condenser 26 by means of which the circuit is tuned to resonance at the frequency of the current supplied by generator G1. An electromotive force is induced in secondary winding 25 due to the alternating current supplied to primary winding 24 by generator G1, the value of such electromotive force being governed of course by the condition of the core structure of the receiver AT. The parts are so proportioned that normally, that is, when receiver AT is not in a position for inductive influence by a roadside inductor, a predetermined normal value of electromotive force is induced in secondary winding 25. Such normal value of electromotive force is not changed when the receiver AT is disposed over an inductor whose winding is short circuited with no condenser included in the connection. That is to say, the normal value of electromotive force induced in secondary winding 25 is not changed by the control influence effected at each second inductor of each tandem of the roadside inductors when such second inductor is short circuited. The electromotive force induced in secondary winding 25 is increased to a predetermined higher than normal value when the receiver AT is disposed above a roadside inductor whose winding is short circuited through a condenser. That is to say, the electromotive force induced in secondary winding 25 is increased to a predetermined higher than normal value by the control influence effected at each first inductor of each pair of roadside inductors when such first inductor is short circuited. The electromotive force induced in secondary winding 25 is reduced to a predetermined lower than normal value when the receiver AT is disposed above an inductor whose winding is open circuited. That is to say, a predetermined lower than normal value of electromotive force is created in secondary winding 25 at each roadside inductor whose winding is open circuited.

Secondary winding 25 of receiver AT is connected to control relays A and AR by a receiving circuit including alternative circuit paths, and relays A and AR are conditioned to different positions according to the electromotive forces created in winding 25 by the particular combination of two control influences effected by the two inductors of a control point, the position of relays A and AR effected at a control point being retained until the train reaches the next control point. In order that relays A and AR may be thus conditioned by the normal, higher than normal and lower than normal electromotive

forces created in winding 25, relay A is adjusted for a pick-up electromotive force that corresponds to the higher than normal electromotive force and with a release electromotive force that corresponds to the lower than normal electromotive force, while relay AR is adjusted for the pick-up electromotive force that corresponds to the normal electromotive force and for a release electromotive force that corresponds to the lower than normal electromotive force. Relays A and AR in turn control a two winding stick relay AP, the pick-up circuit of which includes its top winding 32 and front contact 33 of relay A, and the stick circuit of which includes its lower winding 34, its front contact 35 and back contacts 36 and 37 of relays AR and A, respectively. The alternative circuit paths for relays A and AR and the manner whereby the relays are controlled by the electromotive forces created in winding 25 will also appear when the operation of the apparatus is described.

A three-position cab signal CS is selectively controlled by the control relays A, AR and AP.

A brake controlling magnet valve MV is also preferably provided and governed by the control relays A, AR and AP. The brake controlling mechanism governed by the magnet valve MV is not shown for the sake of simplicity since it may take any one of the several well-known standard forms of such mechanism and its specific construction is not a part of our invention. It is sufficient for the present application to point out that such brake controlling mechanism may comprise a warning whistle and a brake controlling valve and that when the magnet valve MV is energized the warning whistle is silent and the brake controlling valve is conditioned to effect the release position of the train brakes, but that when magnet valve MV is deenergized, the warning whistle is sounded and the brake controlling valve is operated to initiate an automatic application on the train brakes.

The train carried apparatus also preferably includes the usual acknowledging means which as shown in Fig. 2 comprises a source of air supply, a manually operable valve AV, a pneumatic relay PV and a stick relay SP. The valve AV is a manually operable two-position valve and when its handle 46 is set at a normal position, that is, the position illustrated by the solid lines in the drawing, a valve 47 is set to connect an acknowledging reservoir 48 to the train air supply and pressure is stored in reservoir 48. When handle 46 is moved to the position illustrated by the dotted line in the drawing, the train supply is shut off and reservoir 48 is connected to the diaphragm chamber of the pneumatic relay PV which causes the relay PV to be actuated and close a circuit controlling contact 49. Relay SP is a two-winding relay, its pick-up winding 50 being energized over an obvious circuit including contact 49 of relay PV, and its second winding 51 being energized by a stick circuit extending from terminal B of a convenient source of current such as a battery not shown, over back contacts 37, 36 and 52 of relays A, AR and AP, respectively, front contact 53 of relay SP, winding 51 of the relay and to terminal C of the same source of current. Thus relay SP is picked up due to manual operation of valve AV, and is retained picked up as long as the control relays A, AR and AP are released. Relay SP controls the circuits for magnet valve MV as will shortly appear.

In describing the operation of the apparatus we shall assume that in Fig. 1 a train indicated conventionally at TN occupies the section next in advance of section E—F with the result that both inductors FA1 and FA2 associated with such section next in advance are open circuited; the first inductor EA1 of the two inductors associated with the section E—F is short circuited and the second inductor EA2 is open circuited; and the inductors DA1 and DA2 associated with section D—E are both short circuited. We shall also assume that the train carried apparatus of Fig. 2 has been established at its clear signal indication condition in a manner to later appear, that is, the apparatus of Fig. 2 occupies the position shown in the drawing. Under such clear signal indication condition of the apparatus of Fig. 2, it is to be observed that relay A is connected to the winding 25 over a circuit path that includes its own front contact 54, with the result relay A is held picked up by the normal value of electromotive force created in winding 25, it being recalled relay A is adjusted for a release electromotive force that corresponds to a predetermined lower than normal value of electromotive force. Also it is to be observed that stick relay AP is picked up over its pick-up circuit including front contact 33 of relay A. Furthermore, with relays A and AP picked up, an operating circuit is formed for signal CS and also for magnet valve MV. The circuit for signal CS extends from terminal B over front contact 38 of relay AP, front contact 39 of relay A, lamp G and terminal C, and lamp G is illuminated to cause the display of a green light for a clear signal indication. The circuit for magnet valve MV includes terminal B, front contact 38 of relay AP, front contact 39 of relay A, a second front contact 43 of relay AP, back contact 44 of relay SP and winding of magnet valve MV to terminal C, and magnet valve MV is energized to effect the release condition of the train brake controlling mechanism.

We shall next describe the operations of the apparatus of Fig. 2 when the train on which such apparatus is mounted moves through the track sections D—E and E—F of Fig. 1 with the train TN occupying the section next in advance of section E—F. At control point D, the receiver AT on passing over the first inductor DA1 inductively receives a control influence that causes the predetermined higher than normal electromotive force in winding 25 and control relay A is retained energized and picked up since such higher electromotive force energizes relay A to a higher degree. At the second inductor DA2, the control influence transmitted to the receiver AT causes no change in the electromotive force created in winding 25 and relay A remains picked up by the normal value of electromotive force. Consequently the clear signal indication condition of the train carried apparatus remains in effect as the train passes through the section D—E, lamp G being illuminated to display a clear cab signal and magnet valve MV being energized to hold the train brake controlling mechanism in its release position.

When receiver AT passes over the first inductor EA1 at control point E, the control influence causes the predetermined higher than normal value of electromotive force to be created in winding 25 because inductor EA1 is short circuited and relay A is retained picked up. At the second inductor EA2 the control influence

causes the predetermined less than normal electromotive force to be created in secondary winding 25 because inductor EA2 is open circuited with the result that relay A is released. Stick relay AP is now retained energized over its stick circuit including back contacts 37 and 36 of relays A and AR, respectively, and control relays A and AR are connected in series to the winding 25 by a circuit path extending from the left-hand terminal of winding 25 over front contact 55 of stick relay AP, winding of relay AR, back contact 56 of relay A, winding of relay A and to the right-hand terminal of winding 25. Thus as soon as the receiver AT passes off inductor EA2 and the normal value of electromotive force is induced in secondary winding 25 and applied to relays A and AR in series, the relay AR is picked up and the relay A remains released due to their respective pick-up electromotive forces. With control relay AR picked up opening back contact 36, the stick circuit for relay AP is opened and relay AP is immediately released. Since front contact 57 of relay AR serves to shunt front contact 55 of relay AP, the two relays A and AR remain connected in series to winding 25 so that relay AR is picked up and relay A is released due to the normal value of electromotive force. With relay AR picked up and relays A and AP released an approach operating circuit is formed for signal CS and magnet valve MV, the operating circuit for signal CS extending from terminal B over back contact 40 of relay AP, front contact 41 of relay AR, lamp Y and terminal C, and lamp Y is illuminated to cause signal CS to display a yellow light for an approach signal indication. The magnet valve circuit includes terminal B, back contact 31 of relay A, front contact 58 of relay AR, back contact 59 of relay AP, back contact 44 of relay SP, winding of magnet valve MV and terminal C. It follows that an approach cab signal is displayed and magnet valve MV is energized while the train traverses track section E—F.

When the receiver AT passes over the first inductor FA1 at control point F, the control influence transmitted to the receiver AT causes the predetermined lower than normal electromotive force to be created in winding 25 and relay AR is released, it being recalled that relay AR is adjusted for a release electromotive force which corresponds to such lower than normal value of electromotive force. At the second inductor FA2 the control influence transmitted to the receiver AT also causes the predetermined lower than normal value of electromotive force to be created in winding 25. With relay AR released the control relay A is connected to winding 25 by a circuit path extending from the left-hand terminal of winding 25 over back contact 60 of relay AR, a resistor 61, winding of relay A and to the right-hand terminal of winding 25. Relay A is not picked up by the normal value of electromotive force created in winding 25 when the receiver passes off the roadside inductor due to the high pick-up electromotive force provided for relay A, the resistor 61 interposed in the circuit path aiding to prevent relay A from being picked up by such normal value of electromotive force. With the three control relays A, AR and AP all released an operating circuit is formed from terminal B over back contact 40 of relay AP, back contact 42 of relay AR and lamp R to terminal C, and lamp R is illuminated to cause the signal CS to display a red light as a slow speed cab signal indication. Magnet MV is now

deenergized and to acknowledge the slow speed signal indication and reenergize the magnet MV the operator would actuate handle 46 to its dotted line position and actuate the pneumatic relay PV and cause the picking up of the acknowledging relay SP. Relay SP on picking up closing front contact 45 completes an alternative circuit for energizing the magnet valve to forestall an automatic brake application. Hence a slow speed cab signal indication is displayed by the apparatus of Fig. 2 as the train on which it is mounted moves into the section already occupied by the train TN, and an automatic brake application is initiated unless the operator acknowledges such slow speed indication.

Assuming that with the slow speed signal indication condition established for the apparatus of Fig. 2 and the train on which it is mounted encounters a control point at which an approach traffic condition is reflected by the roadside inductors, that is, a control point similar to control point E of Fig. 1, the higher than normal value of electromotive force is created in winding 25 at the first inductor because its winding is short circuited through a condenser. Such higher than normal electromotive force is effective to pick up relay A which is connected to winding 25 over back contact 60 of relay AR. Relay A on picking up connects relay A to winding 25 over the circuit path including its own front contact 54 so that the relay is held picked up after the receiver passes off such first inductor. Relay A on picking up also closes front contact 33 and completes the pick-up circuit for relay AP and that relay is picked up. Since at such approach control point the second inductor is open circuited, relay A is released when the receiver AT passes over the second inductor due to the lower than normal electromotive force created in winding 25, and with relay A released and relay AP picked up, relays A and AR are connected in series to the winding 25 so that relay AR is picked up by the normal electromotive force created in winding 25 when the receiver passes off the second inductor. It follows that the approach cab signal indication condition is established for the apparatus of Fig. 2 at such approach control point of the roadside apparatus.

Again assuming that the slow speed indication condition exists for the apparatus of Fig. 2 and the train encounters a control point such as control point D of Fig. 1 and at which the inductors are set to reflect a clear traffic condition, relay A is picked up in response to the higher than normal value of electromotive force created by the control impulse transmitted by the first inductor and relay A is then retained picked up by the no change in the normal value of electromotive force effected by the control impulse transmitted at the second inductor, and consequently the clear signal indication condition of the train carried apparatus is established.

In the event the approach signal indication condition exists for the apparatus of Fig. 2 and the train encounters a control point at which the inductors are set to reflect clear traffic condition, relays A and AR are connected in series to winding 25 and relay A is picked up by the higher than normal value of electromotive force created by the control impulse of the first inductor. Relay A on being picked up to open back contact 56 and close front contact 54 disconnects the control relay AR and connects its own winding to winding 25 so that relay AR is released and relay A is held picked up. At the second inductor the

control impulse is such that no change is made in the normal value of electromotive force of winding 25, and relay A remains picked up and consequently the clear signal indication condition is established.

In case the train carried apparatus is set at the clear signal indication condition and the train encounters a control point such as location F where the inductors are conditioned to reflect a stop or slow speed traffic condition, relay A is released at the first inductor due to the lower than normal value of electromotive force created in winding 25. Relay AP is retained energized over its stick circuit and relay AR is picked up by the normal value of electromotive forces during the interval the receiver is passing from the first to the second inductor. At the second inductor relay AR is released due to the lower than normal value of electromotive force created in winding 25 and consequently all three control relays A, AR and AP are released as the receiver passes off the second inductor and the slow speed signal indication condition is established for the train carried apparatus.

From the foregoing description it is to be seen that the picking up of a control relay A or AR to establish either the clear or approach signal indication is effected only when the proper pre-selected combination of two successive control influences are received and consequently the establishing of a proceed cab signal by a wrong control influence is eliminated. Furthermore it is clear that we have provided simple and inexpensive railway traffic controlling apparatus organized into a novel intermittent inductive three-position cab signal and train control system.

Although we have herein shown and described only one form of railway traffic controlling apparatus embodying our invention, it is understood that various changes and modifications may be made therein within the scope of the appended claims without departing from the spirit and scope of our invention.

Having thus described our invention, what we claim is:

1. Railway traffic controlling apparatus comprising; traffic controlled roadside means operable to a clear, an approach and a slow speed condition; said means including two spaced inductors with each inductor constructed to transmit either one of two different control influences and said means arranged for the two inductors to transmit a different combination of two control influences for each of said conditions, a train carried receiver having a winding and means for creating an electromotive force in said winding, said receiver mounted for inductive relationship to each of said inductors to create a different predetermined value of said electromotive force for each of said control influences; train carried relay means connected to said winding and operable to a clear, an approach and a slow speed position in response to the two successive electromotive forces created by the combination of control influences transmitted by the clear, approach and slow speed conditions respectively of the roadside means; and a cab signal controlled by said relay means to display a clear, an approach and a slow speed signal according to the clear, approach and slow speed positions respectively of the relay means.

2. Railway traffic controlling apparatus comprising, roadside means including a first and a second inductor in tandem; each of said inductors comprising a magnetizable core and a winding

mounted thereon and adaptable of effecting a different control influence according as its winding is short circuited through a condenser, is short circuited or is open circuited; traffic controlled means to control the connections of said inductor windings to effect a distinctive combination of two control influences for clear, approach and slow speed traffic conditions respectively; a train carried receiver having a winding and means to create an electromotive force in its winding, said receiver mounted for inductive relationship to said inductors to create a different predetermined value of said electromotive force for each of said control influences; and train carried signaling apparatus connected to said receiver winding to display a clear, an approach and a slow speed indication in response to said clear, approach and slow speed combination of control influences respectively.

3. Railway traffic controlling apparatus comprising, a pair of roadside inductors at each of a plurality of different control points along a railway, the inductors of each pair arranged in tandem and each inductor comprising a magnetizable core and a winding mounted thereon and adaptable of transmitting a different control influence according as its winding is short circuited through a condenser, is short circuited or is open circuited; traffic controlled means at each said control point to control the connections of the windings of the inductors at the same control point to effect a distinctive combination of two control influences for clear, approach and slow speed traffic condition respectively, a train carried receiver having a winding and means to create an electromotive force in its winding, said receiver mounted for inductive relationship to said roadside inductors to create a different predetermined value of said electromotive force for each of said control influences; and train carried signaling apparatus connected to said receiver winding to display a clear, an approach and a slow speed indication in response to the electromotive forces created by said clear, approach and slow speed combination of control influences respectively transmitted at each of said control points.

4. Railway traffic controlling apparatus comprising, a first and a second inductor disposed in tandem at a control point along a railway; each of said inductors comprising a magnetizable core and a winding mounted thereon and adaptable of transmitting a different control influence according as its winding is short circuited through a condenser, is short circuited or is open circuited; traffic controlled means at said control point to short circuit the winding of the first inductor through a condenser and to short circuit the winding of the second inductor, to short circuit the winding of the first inductor through a condenser and open circuit the winding of the second inductor, and to open circuit the windings of both inductors under clear, approach and slow speed traffic conditions respectively; a train carried receiver having a winding and means to create an electromotive force in its winding, said receiver mounted for inductive relationship to said inductors to create at said control point a different combination of two electromotive forces in the receiver winding in response to the control influences for said clear, approach and slow speed traffic conditions of the inductors, and train carried signaling means connected to said receiver winding operated to a clear, an approach and a slow speed signal condition in response to the

5 clear, approach and slow speed combination of electromotive forces respectively.

5. Railway traffic controlling apparatus comprising, a first and a second roadside inductor at each of a plurality of control points along a railway, the inductors at each control point disposed in tandem along one side of the track and each inductor comprising a magnetizable core and a winding mounted thereon and adaptable of transmitting a high, a no change or a low control influence according as the inductor winding is short circuited through a condenser, is short circuited or is open circuited respectively; means at each of said control points to short circuit the winding of the first inductor through a condenser and to short circuit the winding of the second inductor, to short circuit the winding of the first inductor through a condenser and to open circuit the winding of the second inductor, and to open circuit the windings of both inductors under clear, approach and slow speed traffic conditions respectively in advance of such control point; and train carried receiving means including a winding and a current source to create an electromotive force in the winding and said receiving means differently responsive to such high, no change and low control influences and disposed to be successively influenced by said inductors as the train passes a control point to display a clear, an approach and a slow speed signal indication in response to the different combinations of two control influences effected under clear, approach and slow speed traffic conditions respectively.

6. Railway traffic controlling apparatus comprising, a train carried receiver having a winding and means for creating a normal electromotive force in said winding, a first and a second train carried relay, said first relay adjusted for a predetermined higher than said normal pick-up electromotive force and for a predetermined lower than said normal release electromotive force, said second relay adjusted for a pick-up electromotive force corresponding to said normal electromotive force and for said lower than normal release electromotive force, a stick relay; said first relay connected to said receiver winding either over a path including a back contact of said second relay or over a path including its own front contact, said first and second relays connected in series to said receiver winding either over a path including a front contact of said stick relay and a back contact of said first relay or a path including a front contact of the second relay and said back contact of the first relay, said stick relay provided with a pick-up circuit including a front contact of said first relay and a stick circuit including a back contact of each of said first and second relays, a three-position cab signal selectively controlled as to its position by said first and second relays, and traffic controlled roadside means disposed for inductive relationship to said receiver and effective to successively create in said receiver winding said high and said normal electromotive forces to pick up the first and stick relays under clear traffic condition, to successively create in the receiver winding said high and said low electromotive forces to pick up said second relay under approach traffic condition, and to successively create in the receiver winding said low electromotive forces to release both the first and second relays under slow speed traffic condition.
